UNITED STATES PATENT OFFICE.

JAMES H. MEEHAN, OF PHILADELPHIA, PENNSYLVANIA.

DESIGN FOR A LADLE.

Application filed November 28, 1924. Serial No. 11,502. Term of patent 3½ years.

To all whom it may concern:

Be it known that I, JAMES H. MEEHAN, a citizen of the United States, residing in Philadelphia, Pennsylvania, have invented a certain new, original, and ornamental Design for a Ladle, of which the following is a specification, reference being had to the accompanying drawing, in which:—

Figure 1 is a perspective view illustrating my new design for a ladle; and Fig. 2 is a longitudinal sectional view.

I claim:

The ornamental design for a ladle, substantially as shown.

JAMES H. MEEHAN.
